UNITED STATES PATENT OFFICE

169,306

INTAKE MANIFOLD FOR INTERNAL-
COMBUSTION ENGINES

Max H. Ellis, Montebello, Calif.

Application June 10, 1952, Serial No. 20,113

Term of patent 14 years

(Cl. D77—1)

To all whom it may concern:

Be it known that I, Max H. Ellis, a citizen of the United States of America, residing at 900 Washington Avenue, Montebello, California, in the county of Los Angeles, State of California, have invented a new, original, and ornamental Design for an Intake Manifold for Internal Combustion Engines, of which the following is a specification, reference being had to the accompanying drawing, forming a part hereof:

Fig. 1 is a perspective view of an intake manifold for internal combustion engines, showing my new design;

Fig. 2 is an elevational view of the end not shown in Fig. 1;

Fig. 3 is a bottom view of the manifold; and

Fig. 4 is an elevational view of the side not shown in Fig. 1.

The dominant feature of my design resides in the portions shown in solid outline.

I claim:

The ornamental design for an intake manifold for internal combustion engines, substantially as shown and described.

MAX H. ELLIS.
